UNITED STATES PATENT OFFICE.

WILLIAM H. EVER, OF CLEVELAND, OHIO.

CONCRETE FLOORING CONSTRUCTION.

1,273,344.

Specification of Letters Patent. Patented July 23, 1918.

Application filed January 17, 1914. Serial No. 812,701.

To all whom it may concern:

Be it known that I, WILLIAM H. EVER, a citizen of the United States, residing at Cleveland, in the county of Cuyahoga and 5 State of Ohio, have invented a new and useful Improvement in Concrete Flooring Constructions, of which the following is a specification.

This invention relates generally to reinforced concrete constructions and more particularly to a reinforced concrete floor construction.

The object of my invention is to provide a reinforced concrete floor and ceiling construction of uniform dead load irrespective of span, and also a reinforced floor and ceiling construction of uniform height irrespective of live load and also a construction of uniform dead load and height irrespective 20 of span and live load.

The invention also has for its object the construction of a floor of very light weight and at the same time provide unusually large air spaces which can be utilized for 25 the arrangements of pipes or conduits and which will also aid in making the construction sound proof.

Heretofore floors have been constructed with hollow tile or a combination of iron 30 beams and hollow tile or of solid slabs of reinforced concrete.

In all of these constructions the depth varies with the spans and with the load they are called upon to carry. Ordinarily they 35 are not sound proof without the addition of some deadening material which adds materially to the weight and cost of the floor construction.

My invention comprehends the employment of a series of reinforced concrete beams 40 in combination with slabs of plastic material, said reinforced concrete beams and slabs being of constant depths and constant weights, the only varying element being the reinforcement which varies with the span and with the live load.

My invention consists also in certain details of construction and novelties of combination and arrangement all of which will 50 be fully described hereinafter and pointed out in the claims.

In the drawings forming a part of this specification:

Figure 1 is a cross sectional view of a 55 portion of a concrete floor and ceiling construction embodying my invention the rein-

forced concrete beams being T-shape in cross section.

Fig. 2 is a similar view in which reinforced concrete I-beams are employed. 60

Fig. 3 is a detail perspective view of the positioning wire employed in the T-beam.

Fig. 4 is a detail perspective view of the positioning wire employed in the I-beam.

Fig. 5 is a perspective view illustrating 65 the details of construction and the arrangement of the various parts constituting my invention.

Referring to the drawings A indicates the reinforced T-beams and B the reinforced concrete I-beams and C indicates the slab of cement or other plastic material arranged upon these beams and D represents the ceiling below, which is attached to the bases of the beams in any approved manner. 70 The reinforced concrete beams are manufactured and then transported to the point of erection and are arranged or supported in a building exactly the same as a metallic beam or girder would be arranged 80 and supported, the distances between centers being governed by the character of the structure desired.

In order that these beams can be manufactured at one point and readily transported and erected they must be of minimum weight and of constant end sections and in order to accomplish this the metallic 85 reinforcements must be arranged and held at the proper points in order to utilize the 90 maximum compression, tension and shear strength of the steel reinforcement.

The positioning of the longitudinal reinforcements is secured by means of positioning wires E and F which I have illustrated 95 in Figs. 3 and 4 respectively and which are also shown in connection with the T and I-beams. In the T beam construction one central tension wire or rod G and two side wires or rods G' are employed and one compression wire or rod H, these wires or rods being absolutely positioned by means of the positioning wire E which is coiled upon itself to provide the central positioning eye E' and the side positioning eyes E² and the 100 upper positioning eye E³, the members of the wire crossing as shown at E⁴ and the free ends E⁵ projecting upwardly from the top of the beam and are intended to be bent down in opposite directions as shown in full 110 lines in Fig. 3 and for a purpose hereinafter explained. The cross portions of the wire

serve as the necessary shear rods within the web of the beam. In the I-beam construction there is employed the central tension wire G and side tension wires or rods G' and in addition to the central compression wire H there are employed two side compression wires or rods H', these wires or rods being absolutely positioned by means of the positioning wires F, shown in detail in Fig. 4, 10 each wire being bent to provide the central positioning eye F' and side positioning eyes F² for the tension wires or rods and the central eye F³ and side eyes F⁴ for positioning the compression wires or rods H and H' and 15 the ends of the wire F' are carried out through the top of the beam and extend a considerable distance, being adapted to be bent down in opposite directions, so as to overlap as shown in Figs. 1 and 2, thereby 20 providing the end shear rods or reinforcing members in the floor slab C, these overlying slabs C forming the flooring proper by enveloping and combining of these positioning and shear wires becoming an essential and 25 unit part of the compression section of the floor construction. The ceiling D as previously stated is attached to the bottom of the beams in any suitable manner.

The tie or positioning wires E and F are 30 manufactured with their ends left of proper length to serve as shear and compression rods in the upper slab. These tie or positioning rods exactly space and properly position the longitudinal wires or rods G and 35 G', and H and H'.

The assembled steel frame work is then positioned in rigid molds in the shop ready to receive the concrete or other cementitious material which is of a consistency to readily 40 pour in the mold and around the assembled steel. After proper setting of the concrete the mold is removed and the beams are ready for transportation and erection on the building site, and may be set to twenty-four 45 inch centers ready to receive the slab C and plastic ceiling D. Temporary forms between the beam, blocked against the lower flanges, or a metal lathing for the beams may be used upon which the projecting ends 50 of the tie rods are now bent down into proper position, these downwardly bent ends overlapping as most clearly shown in Figs. 1 and 2. The slab of minimum section is then poured of concrete or other cementitious material, adhesion to the tops of the beams being secured either by scarifying the upper flange or by providing a groove as indicated in Figs. 2 and 5. The slab completely envelopes the projecting tie rod ends 55 acting as shear rods and uniting the various parts into a combined whole. After the slab has set, the forms are removed and the ceiling applied according to any method.

From an examination of Figs. 1 and 2 and 60 65 it is evident that nearly sixty per cent. of

the cross sectional area is air space which can be utilized for conduits installation and ventilation and these large air spaces also provide a sound proof and moisture proof floor.

It will be therefore seen that I provide a novel floor construction which is strong and durable and at the same time economical in the employment of materials, and at the same time providing a floor of maximum 75 strength and minimum weight.

What I claim is:—

1. A concrete floor construction comprising a plurality of spaced apart beams and an overlaying layer or slab, a series of tie or 80 positioning wires each of which is coiled upon itself in such a manner as to lie substantially in a single plane and formed with an upper and a plurality of separated lower positioning eyes or coils and the sections of the wires between said eyes being double and intersecting each other, said positioning wires arranged at definite and separated intervals in said spaced beams and adapted to receive longitudinal reinforcing bars in 85 said eyes or coils, an upper longitudinal reinforcing compression bar supported within the upper positioning eyes or coils, a lower longitudinal reinforcing tension bar supported within each of the lower positioning 90 eyes or coils, the ends of each of the said tie or positioning wires being bent laterally and in opposite directions for reinforcing said overlying layer or slab.

2. A concrete floor construction comprising a plurality of spaced apart beams and an overlaying layer or slab, a series of tie or 100 positioning wires each of which is made from a single piece and coiled upon itself in such a manner as to lie substantially in a single plane and formed with a plurality of separated upper and a plurality of separated lower positioning eyes or coils and the sections of the wires between said eyes being double and intersecting each other, said positioning wires arranged at definite and separated intervals in said spaced beams and adapted to receive longitudinal reinforcing bars, upper longitudinal reinforcing compression bars supported within each of the 105 upper positioning eyes or coils, a lower longitudinal reinforcing tension bar supported within each of the lower positioning eyes or coils, the ends of each of the said tie or positioning wires being bent laterally and 110 in opposite directions for reinforcing said overlying layer or slab.

3. As a new article of manufacture an element for concrete floor construction comprising a positioning wire which is made from a single piece and coiled upon itself in such a manner as to lie substantially in a single plane and formed with separate upper and lower positioning eyes or coils and the sections of the wire between the eyes being 115 120 125 130

double and intersecting each other, said positioning eyes or coils adapted to receive either a compression or tension longitudinal reinforcing bar and the ends of the said tie or positioning wire being adapted to be bent laterally and in opposite directions in the plane of the positioning wire.

4. As a new article of manufacture an element for concrete floor construction comprising a positioning wire which is made from a single piece and coiled upon itself in such a manner as to lie substantially in a single plane and formed with a plurality of separated upper and lower positioning eyes

or coils and the sections of the wire between the eyes being double and intersecting each other, and each of said positioning eyes or wire adapted to receive either a compression or tension longitudinal reinforcing bar and the ends of the said tie or positioning wire being adapted to be bent laterally and in opposite directions in the plane of the positioning wire.
